O. J. PARKS

VALVE EQUIPPED CONTAINER

Filed June 16, 1927.

Inventor:
Ostrander J. Parks
By J. W. Forth, Sec., C. H. T. & W. L. L.,
Atty.

UNITED STATES PATENT OFFICE.

OSTRANER J. PARKS, OF RIVER FOREST, ILLINOIS, ASSIGNOR TO GENERAL AMERICAN TANK CAR CORPORATION, OF CHICAGO, ILLINOIS, A CORPORATION OF WEST VIRGINIA.

VALVE-EQUIPPED CONTAINER.

Application filed June 16, 1927. Serial No. 199,236.

My invention relates more particularly to containers equipped with valves, especially for the lower, discharge, outlets thereof, of the type which are moved toward and away 5 from the seats with which they cooperate, by rotation in one direction or the other, as for example by providing threaded engagement between the valve mechanism and a relatively stationary part of the container structure.

10 I have devised my invention for use more particularly, though not exclusively, in tank cars in which valve mechanisms control the lower outlets thereof and wherein, under vibration to which the valve mechanisms are 15 subjected in travel over the tracks and the lashing of the contents of the tank, danger of the valves becoming backed off their seats is presented.

My primary objects are to provide means 20 whereby danger of accidental backing off of the valves, and resulting in leakage of the contents of the tanks, is prevented; to provide a simple, positively operating and economical construction of means for accomplishing this 25 purpose; to provide means for this purpose which will become automatically operative upon the seating of the valve, thereby avoiding the necessity of relying upon the operator setting the mechanism into functioning position; to provide means functioning as above 30 stated and so constructed that should the vertical diameter of the tank become increased, as for example by the turning of the tank on its side, as in the case of an accident, the discharge valve will not become opened and 35 without subjecting the parts of the valve mechanism and other parts associated therewith from becoming unduly strained; and other objects as will be manifest from the following description.

Referring to the accompanying drawing, in which I have illustrated my invention as applied to the lower, discharge, opening of a tank car, the view therein shown is a 45 vertical sectional elevation through the portion of the tank car at which the outlet opening and the valve mechanism therefor is located, certain parts of the car and a portion of the rod of the valve mechanism, being omitted.

In the particular arrangement shown the dome, such as that commonly provided as a part of the tank cars, is represented at 1, the

manhole therein being indicated at 2 and shown as closed by a cover 3. The plate portion 4 represents the bottom of the tank and contains the lower discharge opening 5 affording a valve seat 6 and through which the contents of the tank may be discharged.

55 The outlet 5 is controlled by valve mechanism represented generally at 7 and shown as comprising a valve proper 8 adapted to cooperate with the valve seat 6 and carried by the lower end of valve-actuating means comprising a lower bar section 9 and an upper 60 bar section 10 connected together for rotation as a unit. The lower bar section 9 with the lower end of which the valve 8 is operatively connected, is externally threaded as represented at 11 at which it engages the 65 thread of a threaded opening 12 in a plate 13 supported above the bottom plate 4 by studs 14 connected with the latter, the upper end of the section 9 being shown as forked 15 to receive the lower end of the rod section 10 which 70 is connected thereto by a pin 16.

75 The rod section 10 is non-circular in cross section, it being shown as of square cross section, and extends upwardly through, and is rotatable in, an opening in a bracket 17 secured to and extending inwardly from, the vertical wall of the dome 1.

80 Slidable up and down on the rod section 10, above the bracket 17, is a hand wheel 18, the opening through the latter being of the same shape as the cross-sectional shape of the 85 rod section 10, to cause the wheel 18 and rod to rotate as a unitary structure, the rod section 10 at its upper end being provided with a stop pin 19 which normally operates to prevent the wheel 18 from being lifted off the rod section 10 but which is of such material and size that it will yield and permit the wheel to 90 become disengaged from the rod and not overstrain the valve and the other parts of the valve mechanism adjacent thereto, or permit the valve to become unseated, in case of 95 accident.

100 The tendency of valve mechanism of the type shown, when the car is in transit, is to rotate in a direction to lift the valve 8 from the seat 6, this tendency being overcome, according to the preferred illustrated embodiment of my invention, by providing means which operate automatically in the travel of 105 the car over the track, to exert against the

valve mechanism continuing force tending to screw the valve mechanism in a direction for moving the valve toward its seat, but without exerting such a pressure as to damage the valve or the seat. The means shown comprise a pair of oppositely disposed cooperating cam members 20 and 21, the cam member 20 depending from the hand-wheel 18 and being shown as in the form of a sleeve-like member with its lower edge shaped to afford a cam; and the cam member 21 being shown as in the form of a plate resting upon the upper surface of the bracket 17 and secured thereto by the bolts 22 with an upwardly extending boss portion the upper surface of which presents the lower cam, this plate with its boss portion containing a vertically disposed circular opening registering with the opening in the bracket 17 and through which the rod section 10 upwardly extends and in which the latter is rotatable.

The operation of the mechanism is as follows:

Assuming the valve 8 to have been lowered against the seat 6, as shown in the drawing, by the operator rotating the hand wheel 18, the latter having been preferably preliminarily raised to a position in which the cam 20 clears the cam 21, the release of the grasp of the operator on the hand wheel 18 causes it to descend on the rod section 10 to engage its cam 20 with the cam 21. The wheel 18 having been applied to such an annular position upon the rod section 10 that its cam surface 20 will occupy substantially the position shown in the drawings relative to the cam surface 21 when the valve is in seated position, the tendency of the cam member 20, under the combined weight of this member and the wheel 18, is to slide down the cam 21 and thus exert on the rod section 10 force tending to rotate it in clockwise direction and thus tending to press the valve 8 toward the seat 6. Thus vibrations produced in the valve mechanism and which would have a tendency to unscrew the rod from the support 13 are caused to produce a directly opposite effect, namely, rotation of the rod in a direction to seat the valve.

Furthermore, the provision of the cam mechanism as described operates to prevent lateral vibration of the rod in the opening in the bracket 17 thus steadyng the valve rod, preventing vibration thereof and avoiding undue wear of these parts.

The hand-wheel 18 being slidale along the rod section 10, variations in the vertical distance between the threaded support 13 and the bracket 17, such as occur under variations in loading of the car and the shifting movement of its contents or distortion of its walls, particularly in case of accident, do not result in the subjecting of the valve mechanism, or the parts associated therewith, to undue strains and have no effect on the proper

functioning of the cam mechanism described, which automatically adjusts itself to such variations. Should the vertical distance referred to become excessive, the safety pin 19 will yield, permitting the hand wheel to disengage from the rod section 10 to avoid undue strains on the parts referred to and ensure against accidental opening of the valve 8 and the discharge of the contents of the car.

While I have illustrated and described a particular construction embodying my invention and shown a particular embodiment thereof, I do not wish to be understood as intending to limit it thereto as it may be used in other situations and the form of its embodiment modified and altered without departing from the spirit of my invention.

What I claim as new, and desire to secure by Letters Patent, is:

1. In combination, a member having a valve seat, valve mechanism comprising a valve proper for engaging said seat and an operating rod having threaded engagement with a stationary part of the structure whereby said valve proper is movable toward and from said seat, and cam means operated automatically to resist accidental rotation of said valve mechanism in a direction to unseat said valve proper.

2. In combination, a member having a valve seat, valve mechanism comprising a valve proper for engaging said seat and an operating rod having threaded engagement with a stationary part of the structure whereby said valve proper is movable toward and from said seat, and weight-operated cam means operated automatically to resist accidental rotation of said valve mechanism in a direction to unseat said valve proper.

3. In combination, a member having a valve seat, valve mechanism comprising a valve proper for engaging said seat and an operating rod having threaded engagement with a stationary part of the structure whereby said valve proper is movable toward and from said seat, and cam means operated automatically to exert force on said valve mechanism tending to rotate the latter in a direction for moving said valve proper toward said seat.

4. In combination, a member having a valve seat, valve mechanism comprising a valve proper for engaging said seat and an operating rod having threaded engagement with a stationary part of the structure whereby said valve proper is movable toward and from said seat, and weight-operated cam means operated automatically to exert force on said valve mechanism tending to rotate the latter in a direction for moving said valve proper toward said seat.

5. In combination, a member having a valve seat, valve mechanism comprising a valve proper for engaging said seat and an operating rod, said valve mechanism being

rotatable to move said valve proper toward and from said seat, an operating member on said rod for rotating the latter and movable along said rod, and means formed of cooperating parts one of which is stationary and the other of which is on said operating member for resisting accidental rotation of said valve mechanism in a direction to unseat said valve proper.

10 6. In combination, a member having a
valve seat, valve mechanism comprising a
valve proper for engaging said seat and an
operating rod, said valve mechanism being
rotatable to move said valve proper toward
15 and from said seat, an operating member on
said rod for rotating the latter and movable
along said rod and tending to move in one
direction therealong, and means formed of
cooperating parts one of which is stationary
20 and the other of which is on said operating
member, said first-referred-to part being
adapted to engage said second-referred-to
part and rotate said valve mechanism in the
movement of said operating member in the
25 direction in which the latter tends to move.

7. In combination, a member having a valve seat, valve mechanism comprising a valve proper for engaging said seat and an operating rod, said valve mechanism being rotatable to move said valve proper toward and from said seat, an operating member on said rod for rotating the latter and movable along said rod, and cam means formed of co-operating parts one of which is stationary and the other of which is on said operating member, for resisting accidental rotation of said valve mechanism in a direction to unseat said valve.

10 8. In combination, a member having a
valve seat, valve mechanism comprising a
valve proper for engaging said seat and an
operating rod, said valve mechanism being
rotatable to move said valve proper toward
and from said seat, an operating member on
15 said rod for rotating the latter and movable
along said rod and tending to move in one
direction therealong, and cam means formed
of cooperating parts one of which is station-
ary and the other of which is on said operat-
ing member, said first-referred-to part being
50 adapted to engage said second-referred-to
part and rotate said valve mechanism in the
movement of said operating member in the
direction in which the latter tends to move.

55 9. In combination, a member having a valve seat, valve mechanism comprising a valve proper for engaging said seat and an upwardly extending operating rod, said valve mechanism being rotatable to move said valve
60 proper toward and away from said seat, an operating member on said rod for rotating the latter and movable up and down thereon, and means formed of cooperating parts one of which is stationary and the other of which
65 is on said operating member operating in the

lowered position of said operating member to prevent accidental rotation of said valve mechanism in a direction to unseat said valve.

10. In combination, a member having a valve seat, valve mechanism comprising a valve proper for engaging said seat and an operating rod, said valve mechanism being rotatable to move said valve proper toward and from said seat, an operating member on said rod for rotating the latter and movable along said rod, and means formed of cooperating parts one of which is stationary and the other of which is on said operating member operating, in the movement of said operating member in one direction along said rod, to exert force on said valve mechanism tending to rotate the latter in a direction for forcing said valve proper toward said seat. 70 75 80 85

11. In combination, a member having a valve seat, valve mechanism comprising a valve proper for engaging said seat and an operating rod, said valve mechanism being rotatable to move said valve proper toward and from said seat, an operating member on said rod for rotating the latter and movable along said rod, and cam means formed of cooperating parts one of which is stationary and the other of which is on said operating member operating, in the movement of said operating member in one direction along said rod, to exert force on said valve mechanism tending to rotate the latter in a direction for forcing said valve proper toward said seat. 85
90
95

12. In combination, a member having a valve seat, valve mechanism comprising a valve proper for engaging said seat and an upwardly extending operating rod, said valve mechanism being rotatable to move said valve proper toward and away from said seat, an operating member on said rod for rotating the latter and movable up and down thereon, and means formed of cooperating parts one of which is stationary and the other of which is on said operating member operating in the descent of said operating member on said rod to exert force on said valve mechanism tending to rotate the latter in a direction for forcing said valve proper toward said seat. 100 105 110

13. In combination, a member having a valve seat, valve mechanism comprising a valve proper for engaging said seat and an upwardly extending operating rod, said valve mechanism being rotatable to move said valve proper toward and away from said seat, an operating member on said rod for rotating the latter and movable up and down thereon, and cam means formed of cooperating parts one of which is stationary and the other of which is on said operating member operating in the descent of said operating member on said rod to exert force on said valve mechanism tending to rotate the latter in a direction for forcing said valve proper toward said seat. 115
120
125

14. In combination, a member having a 130

valve seat, valve mechanism comprising a valve proper for engaging said seat and an operating rod having threaded engagement with a stationary part of the structure whereby said valve proper is movable toward and from said seat, a stationary cam member, and a second cam member pressing against said first named cam member, said cam members being so constructed and arranged that force may be applied to said valve mechanism tending to rotate the latter in a direction for moving said valve proper toward said seat.

15. In a tank car, the combination with its lower outlet opening having a valve seat, of a stationary bracket on the car extending above said seat, valve mechanism comprising a valve proper for engaging said seat and an operating rod extending upwardly through said bracket member, said valve mechanism being rotatable to move said valve proper from said seat, and means comprising cooperating parts on said bracket and rod operating automatically to exert on said rod turning force tending to rotate said valve mechanism in a direction to move said valve proper toward said valve seat.

16. In combination, a member having a valve seat, valve mechanism comprising a valve proper for engaging said seat and an operating member, said valve mechanism being rotatable by said operating member to move said valve proper toward and from said seat and said valve proper and said operating member being relatively movable in the direction of their length, and means formed of cooperating parts one of which is rotatable with said operating member and the other of which is non-rotatably mounted for resisting accidental rotation of said valve member in a direction to unseat said valve proper.

17. In combination, a member having a valve seat, valve mechanism comprising a valve proper for engaging said seat and an operating member, said valve mechanism being rotatable by said operating member to move said valve proper toward and from said seat and said valve proper and said operating member being relatively movable in the direction of their length, and means formed of cooperating parts one of which is rotatable with said operating member and the other of which is non-rotatably mounted

operating to exert force on said valve mechanism tending to rotate the latter in a direction for forcing said valve proper toward said seat.

18. In combination, a member having a valve seat, valve mechanism comprising a valve proper for engaging said seat and an operating member, said valve mechanism being rotatable by said operating member to move said valve proper toward and from said seat and said valve proper and said operating member being relatively movable in the direction of their length, and cam means formed of cooperating parts one of which is rotatable with said operating member and the other of which is non-rotatably mounted for resisting accidental rotation of said valve member in a direction to unseat said valve proper.

19. In combination, a member having a valve seat, valve mechanism comprising a valve proper for engaging said seat and an operating member, said valve mechanism being rotatable by said operating member to move said valve proper toward and from said seat and said valve proper and said operating member being relatively movable in the direction of their length, and cam means formed of cooperating parts one of which is rotatable with said operating member and the other of which is non-rotatably mounted for resisting accidental rotation of said valve member in a direction to unseat said valve proper.

20. In combination, a member having a valve seat, valve mechanism comprising a valve proper for engaging said seat and an operating rod having threaded engagement with a stationary part of the structure whereby said valve proper is movable toward and from said seat, a rotatable cam member, and a second cam member relative to which said first-named cam member rotates, one of said cam members pressing against the other thereof and said cam members being so constructed and arranged that force may be applied to said valve mechanism tending to rotate the latter in a direction for moving said valve proper toward said seat.

OSTRANDER J. PARKS.
